UNITED STATES PATENT OFFICE.

GEORGE FARRON, OF DETROIT, MICHIGAN, ASSIGNOR TO KALAMAZOO LOOSE LEAF BINDER COMPANY, OF KALAMAZOO, MICHIGAN.

BINDER DEVICE.

1,197,468.

Specification of Letters Patent. Patented Sept. 5, 1916.

Original application filed March 11, 1915, Serial No. 13,826. Divided and this application filed June 24, 1915. Serial No. 36,128.

To all whom it may concern:

Be it known that I, GEORGE FARRON, a citizen of the United States, residing at Detroit, Michigan, have invented certain new and useful Improvements in Binder Devices, of which the following is a specification.

This invention relates to improvements in binder devices.

The main objects of this invention are to provide an improved binder device which facilitates the use of temporary binders or loose sheet holders and facilitates the handling and manipulating of the sheets thereof.

Further objects, and objects relating to details and economies of construction and operation, will definitely appear from the detailed description to follow.

I accomplish the objects of my invention by the devices and means described in the following specification.

The invention is clearly defined and pointed out in the claims.

A structure constituting a preferred embodiment of my invention is illustrated in the accompanying drawing forming a part of this specification, in which:

Figure I is a plan view of my improved binder device with a temporary binder disposed therein illustrating the manner of manipulating and use. Fig. II is a vertical longitudinal section on line corresponding to 2—2 of Fig. I. Fig. III is a perspective view with the binder and sheets removed.

In the drawings similar reference numerals refer to similar parts throughout the several views.

Referring to the drawings, I have shown an embodiment of my invention particularly designed for the type of binder shown in U. S. Letters Patent No. 878,340, dated Feb. 4, 1908 to Harry F. Bushong, and which comprises a pair of chambered covers 1, adjustably connected by means of binding strips 2 to clamp or bind sheets or leaves 3. The adjustment of the binding strip is effected by a screw mechanism 4 in one cover and a ratchet mechanism 5 in the other. The covers are preferably provided with pivoted clamping bars 6 through which the binding strips are disposed.

As the details of the adjusting mechanism of the binder form no part of this invention, I do not describe the same in further detail herein.

I mount a pair of holders designated generally by the numerals 7 and 8 on a pair of supporting base members 9. The holder 7 comprises a side member 10 and an end member 11, while the holder 8 comprises a side member 12 and an end member 13. These holders are disposed with their end members 11 and 13 in an oppositely inclined relation and with their upper edges meeting. The end members have slots 14 therein registering to receive the binding strips 2 of a binder arranged in holders with one cover in each holder and the sheets resting thereon and their ends abutting the end members of the holder. The sheets have notches 15 therein adapted to receive the binding strips, the notches being preferably open notches, that is notches of uniform width so that the sheets may be conveniently engaged with and disengaged from binding strips.

The end member 11 is disposed at an acute angle to the side member 10 so that the sheets 3 are supported with their upper ends in an inclined relation, thereby facilitating the fingering of the sheets. The end 13 is disposed at right angles to the side members 12 so as to facilitate the alining of the ends of the sheets arranged thereon. The side member 12 is preferably provided with uprights 16 mounted upon the base to project upwardly at the ends of the side member. The side members are preferably supported for adjustment. The adjustment in the structure illustrated is effected by the arms 18 having longitudinal slots 19 therein engaged by the clamping bolts 20.

In use, the binder is arranged with one cover in each holder, the sheets in the first instance being arranged in the holder 7. When entries are to be made, the sheets are removed from the holder 7 and after the entries are made thereon, the sheets are arranged in the holder 8. It is a matter of convenience in making up the day's balance sheet to distinguish or assort all the sheets on which entries have been made by offsetting them in holder 8 as shown in Fig. I.

To assist in alining the sheets in their offset or assorting relation, the end member 13 is provided with a rib 21 adapted to engage the notches 15. See Fig. I. The sheets have 5 centrally disposed notches 15' which register with the binding strips when the sheets are thus offset. By thus arranging the sheets they are assorted so that those in which entries have been made or which it is desired 10 to distinguish for other purposes are all identified.

My improved binder device greatly facilitates the use of temporary binders in the keeping of records particularly where it is 15 desired to keep the records on typewriting machines. The sheets are supported so that they are all readily accessible and the wear and tear thereon is minimized.

My present application is a division of 20 my application for Letters Patent filed March 11, 1915, Serial No. 13,826 and certain features thereof are claimed in that case.

Having thus described my invention, what 25 I claim as new and desire to secure by Letters Patent, is:

1. The combination with a temporary binder comprising binding members, binding strips extending between said binding members, of a pair of holders comprising side and end members disposed oppositely, the end members of said holders having 30 openings therein adapted to receive said binding strips, one holder being provided 35 with a guide with which sheets may be engaged to assist in alining such sheets.

2. The combination with loose sheets and a temporary binder therefor comprising binder members and binding strips extending 40 between said binder members, said sheets having binding strip slots in their binding edges, of a pair of holders each comprising side and end members disposed oppositely, the end members of said holders 45 having openings therein adapted to receive said binding strips, one holder being provided with a guide with which slots of sheets may be engaged to assist in alining other slots of the sheets with the binding 50 strips.

3. The combination with loose sheets and a temporary binder therefor comprising binder members and binding strips extending between said binder members, said 55 sheets having binding strip slots therein, of a pair of holders comprising side and end members disposed oppositely with their ends adjacent, the end members of said holders having slots therein adapted to receive said 60 binding strips, said slots and binding strips constituting positioning means for the binder members on said holders, one holder being provided with a guide with which slots of said sheets may be engaged to assist

in alining other slots of said sheets with the 65 binding strips.

4. The combination with loose sheets and a temporary binder therefor comprising separably associated binder members, of a support therefor comprising a pair of oppositely disposed holders each adapted to support one of said binder members with sheets resting thereon, guide means on said support facilitating the positioning of one binder member on one of said holders, and 70 means on said support facilitating the positioning of sheets on such binder member.

5. The combination with loose sheets having slots in their inner ends and a temporary binder therefor comprising a pair of 80 separably associated binder members, of a pair of holders each comprising side and end members disposed oppositely with their end members adjacent so that the binder members may be separated and disposed in 85 said holders with sheets resting thereon, the sheets being transferable from one binder member to the other when so disposed, the end member on one holder being provided with a guide with which said sheet 90 slots may be engaged to assist in alining the sheets.

6. The combination with loose sheets and a temporary binder therefor comprising a 95 pair of separably associated binder members, said sheets having a plurality of registering slots in their binding edges, of a pair of oppositely disposed holders, each adapted to receive one of said binder members and support them in an opposed relation with sheets resting thereon, one of said 100 holders being provided with a guide with which the slots of sheets may be engaged to assist in alining such sheets on the binder member arranged on such holder.

7. The combination with loose sheets and a temporary binder therefor comprising a pair of separably associated binder members, of a pair of oppositely disposed holders each adapted to support one of said 110 binder members with sheets resting thereon, the sheets being transferable from one binder member to the other, and means on one holder to assist in alining the sheets on the binder member arranged thereon.

8. The combination with loose sheets and a temporary binder therefor comprising separably associated binder members, of a pair of oppositely disposed holders each adapted to support one of said binder members with sheets resting thereon, the sheets being transferable from one binder member to the other, said holders being adapted to permit the sheets being arranged on said binder members in alinement or in an offset 115 relation.

9. In a support for temporary binders, the combination of a pair of base members,

- side members disposed in an oppositely inclined relation, end members disposed between said side members to coact therewith, said end members being vertically slotted, 5 slotted supporting arms for said side members, clamping screws on said base members engaging said slotted side member supporting arms whereby said side members are supported for adjustment transversely 10 of their coacting end members, one of said end members being provided with a guide rib with which offset sheets may be engaged to assist in alining their notches with the binding strips, and uprights mounted on 15 said base members to project upwardly at the ends of the side member with which such end member coacts.
10. In a support for temporary binders, the combination of a pair of base members, 20 side members disposed in an oppositely inclined relation, end members disposed between said side members to coact therewith, said end members being vertically slotted, the slots being adapted to receive the binding 25 strips of binders arranged with a binder member in each holder, slotted supporting arms for said side members, clamping screws on said base members engaging said slotted side member supporting arms whereby 30 said side members are supported for adjustment transversely of their coacting end members, one of said end members being provided with a guide rib with which offset sheets may be engaged to assist in alining 35 their notches with the binding strips.
11. In a support for temporary binders, the combination of a pair of base members, 40 side members disposed in an oppositely inclined relation, end members disposed between said side members to coact therewith, said end members being vertically slotted, the slots being adapted to receive the binding strips of binders arranged with a binder member in each holder, one of said end members being provided with a guide rib with which offset sheets may be engaged to assist in alining their notches with the binding strips, and uprights mounted on 45 said base members to project upwardly at the ends of the side member with which such end member coacts.
12. In a support for temporary binders, the combination of a pair of holders each 50 comprising a side and an end member disposed with their end members in an oppositely inclined relation and with the upper edges of the end members meeting, said end members having registering slots therein, the end member of one holder being disposed 55 at an acute angle to its side member whereby the sheets arranged thereon are supported in an inclined relation to facilitate fingering the sheets, the end member of the other holder being disposed substantially 60 at right angles to its side member to assist in alining the sheets arranged thereon, such end member being provided with a guiding rib with which offset sheets may be engaged to assist in alining the sheets, said side members being adjustable laterally of 65 said end members.
13. In a support for temporary binders, the combination of a pair of holders each comprising a side and an end member disposed with their end members in an oppositely inclined relation and with the upper edges of the end members meeting, said end members having registering slots therein adapted to receive the binding strips of a binder arranged in the support with one binding 70 member in each holder, the end member of one holder being disposed at an acute angle to its side member whereby the sheets arranged on the side member with their inner ends abutting the end member are supported 75 with their outer ends in a stepped relation to facilitate fingering the sheets, the end member of the other holder being disposed substantially at right angles to its side member to assist in alining the outer ends of the 80 sheets arranged thereon, such end member being provided with a guiding rib with which offset sheets may be engaged to assist in alining the sheets.
14. In a support for temporary binders, 85 the combination of a pair of holders having side and end members disposed oppositely and with their end members adjacent and having openings therein adapted to receive the binding strips of a binder arranged in the support with one binding member in each holder, one holder being provided with a guide with which notches in the sheets may be engaged to facilitate the alining of such 90 sheets with the binding strips.
15. In a support for temporary binders, the combination of a pair of holders comprising side and end members, said holders being disposed oppositely with their end members adjacent and in an outwardly inclined relation, one end member being provided with a rib-like guide with which notched sheets may be engaged to facilitate 100 the alining of the sheets.
16. In a support for temporary binders comprising a pair of separably associated binder members and binding strips extending between the binder members, the combination of a pair of holders comprising side and end members, said holders being disposed oppositely with their end members adjacent so that when separated a binder member may be disposed in each holder, the end member having openings adapted to receive the binding strips, and means engaging the 110 binding edges of the sheets to facilitate the alining of sheets on the binder member disposed on one holder.

17. In a support for temporary binders comprising a pair of separably associated binder members, the combination of a pair of holders disposed oppositely so that a binder member may be disposed in each holder and sheets arranged thereon and the sheets transferred from one to the other, and means engaging the binding edges of the sheets facilitating the alining of the sheets

on the binder member disposed on one holder.

In witness whereof, I have hereunto set my hand and seal in the presence of two witnesses.

GEORGE FARRON. [L.S.]
